CLAIM

The ornamental design for a combined ceiling fan housing and light shade, as shown and described.

DESCRIPTION

FIG. 1 is a perspective bottom view of a combined ceiling fan housing and light shade.

FIG. 2 is a perspective top view thereof.

FIG. 3 is a reduced side view of the novel ceiling fan of FIG. 1.

FIG. 4 is a reduced bottom view of the novel ceiling fan of FIG. 1; and,

FIG. 5 is a top view of the novel ceiling fan of FIG. 1. The broken lines showing the ceiling mounting cap with downward extending rod in FIGS. 1-3, for illustrative purposes and form no part of the claimed design, and the broken lines showing the blade mounting holes in FIGS. 2, 3, 5, are for illustrative purposes and form no part of the claimed design, and the broken lines showing a generic blade in FIGS. 6-10 are for illustrative purposes and form no part of the claimed design, and the dotted lines showing the mounting flange extensions and holes in FIGS. 16-25 are for illustrative purposes and form no part of the claimed design.

1 Claim, 5 Drawing Sheets
